CLAIM

We claim the ornamental design for a telephone body, as shown and described.

DESCRIPTION

FIG. 1 is the front perspective view of the telephone body showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof; and,

FIG. 7 is the bottom plan view thereof.

The broken lines in the drawing depict portions of the telephone base that form no part of the claimed design. The bounds of the claim includes the shaded surfaces which extend to the broken lines depicting portions of the telephone base that form no part of the claim; but does not

(Continued)

include those broken lines lines depicting portions of the telephone. The unshaded surfaces shown between the solid lines and the broken lines form no part of the claim.

1 Claim, 7 Drawing Sheets
